[57] CLAIM

The ornamental design for a toy lion figure, substantially as shown and described.

DESCRIPTION

FIG. 1 is a front elevational view of a toy lion figure illustrating our new design;

FIG. 2 is a rear elevational view thereof;

FIG. 3 is a side elevational view thereof, the opposite side being substantially a mirror image thereof, except that the tip of the tail is directed in the opposite direction;

FIG. 4 is a top plan view thereof; and

FIG. 5 is a bottom plan view thereof.

FIG. 2

FIG. 4

FIG. 5
